His Attorney.

UNITED STATES PATENT OFFICE.

WILLIAM D. COOLIDGE, OF SCHENECTADY, NEW YORK, ASSIGNOR TO GENERAL ELECTRIC COMPANY, A CORPORATION OF NEW YORK.

ELECTRON-DISCHARGE DEVICE.

1,261,708.

Specification of Letters Patent.

Patented Apr. 2, 1918.

Application filed June 13, 1916. Serial No. 103,557.

To all whom it may concern:

Be it known that I, WILLIAM D. COOLIDGE, a citizen of the United States, residing at Schenectady, county of Schenectady, State of New York, have invented certain new and useful Improvements in Electron-Discharge Devices, of which the following is a specification.

The present invention relates to electron discharge devices, and particularly to a device for the generation of X-rays.

In accordance with my invention, I have provided a device operable with a substantially pure electron discharge comprising a metallic body part preferably acting also as anode, and an insulating part into which the cathode conductors are sealed, the two parts being joined to each other, and means being provided to prevent the accumulation of an electric charge near the joint. In the described embodiment of my invention this means is a conductive member extending within the tube from the metal part past the joint between the two parts. The constricted space between the conductive member and the cathode tube wall prevents the accumulation of harmful electrostatic stresses at the joint as will be hereinafter more fully explained.

30 In the accompanying drawing, Figure 1 is a longitudinal section of an X-ray tube embodying my invention, and Fig. 2 is a longitudinal section of a modification.

The device shown in Fig. 1 comprises an envelop consisting of an inclosure 1 of metal, as, for example, copper, and an inclosure 2, of insulating material such as glass. A section 3 of platinum is welded or soldered to the copper wall at 4 and is sealed 40 to the glass wall at 5. A tube 6 consisting of copper, or other suitable metal is welded, or otherwise joined, to the tube 1 at 4 and extends into the insulating part 2 of the envelop past the joint 5.

45 The cathode comprises a coiled filamentary conductor 7 consisting preferably of tungsten, this being shown on edge. Surrounding the filament is a tube 8, of molybdenum, or other suitable conductive material, 5 acting as a focusing device. One end of the cathode filament is joined to the focusing device and the other end to a conductor 9. Joined to the tube 8 are two wires 10 and 11 which are secured to a split tube 12 of molybdenum, or iron. The wires 9, 10 and

11 are bound together by a bridge 13, suitable insulation being used if the bridge consists of conducting material. The wires 9 and 10 are sealed into the closed end of the tube section 2. The cathode structure is 60 carried by a tube 14 of glass, or other suitable insulating material.

Within the metal end 1 of the device is applied an anode plate, or target 15, consisting of tungsten or other suitable refractory metal. The target is cooled by water, air, or other suitable cooling fluid circulating through a chamber back of the anode into the wall of which are sealed tubes 16 and 17 for supplying and withdrawing the 70 cooling fluid. Opposite the anode is a tube 18 closed with a window 19 of thin metal, glass, or other material relatively transparent to X-rays.

The tube is exhausted of gas to a pressure 75 so low that conduction of electricity can occur between the cathode and the anode across the vacuous space operatively independent of positive gas ionization, as described on pages 409 to 430 in the *Physical Review* for December, 1913. In exhausting the tube, traces of oxids, which are apt to give off gas during the operation of the tube may be removed by introducing hydrogen gas, heating the walls of the tube externally 80 and then reëxhausting to the required low pressure, say, below 0.05 of a micron of mercury pressure.

When the tube is operated, the cathode 7 is heated to incandescence by passage of current and a source of current of suitable voltage is connected at its negative terminal to the cathode and at its positive terminal to the anode housing 1 with which the target plate 15 is in electrical contact. 90 The electrons emitted by the cathode travel under the influence of the electrical field to the anode where X-rays are produced by their impact. The cathode rays are focused by the electrostatic field of the ring 8 to 100 strike a spot of limited area on the target. Some of the X-rays are permitted to leave the tube through the window 19 so as to be available for use.

The electrons also charge the glass wall 105 of the tube to the full cathode potential. Were the tube 6 absent, disruptive discharges would occur at the joint 5 between the glass and the metal wall thereby disintegrating the glass and allowing air to enter the tube, 110

The tube 6 projecting into the tube 2 past the joint between the glass and metal prevents the glass from becoming charged in the vicinity of the seal in the following manner: The first electrons entering the narrow space between the tube 6 and the envelop wall charge the glass near the end of the tube 6 and the following electrons are repelled by the negatively charged glass 10 and are attracted by the positively charged tube 6 so that few if any reach the joint 5.

The tube shown in Fig. 2 is very similar to the tube shown in Fig. 1, with the exception of the anode construction. The 15 cathode rays strike an anode plate 20 consisting of thin metal, as platinum or silver, where X-rays are generated which pass through the cooling fluid contained in an outer housing 21 and out through a window 22 which may consist of thin metal, for example aluminum. If the plates 20 and 21 are made very thin some of the cathode rays will pass through the same and will be emitted from the tube so as to be available for therapeutic or other purposes. In 25 the latter case the outer housing 21 may be omitted so that the cathode rays may emerge directly through the window 20.

While I have described an X-ray tube to 30 illustrate my invention it will apply to a hot cathode rectifier or other electron discharge device.

What I claim as new, and desire to secure by Letters Patent of the United States, is:—

35 1. An electrical discharge device comprising the combination of an envelop consisting of a conducting section and an insulating section sealed to each other, a cathode sealed into said insulating section, coöperating 40 with said conductive section acting as anode, and a reëntrant tubular member connected to the conductive section of said envelop extending into the insulating section thereof,

spaced closely adjacent but out of contact with said envelop. 45

2. An electrical discharge device comprising the combination of an envelop comprising a conductive section and an insulating section sealed to each other, a cathode sealed into said insulating section coöperating with 50 said conductive section acting as anode, and conductive means for carrying the anode potential into the insulating section of said envelop, said means being spaced closely adjacent but out of direct contact with said 55 envelop.

3. An X-ray tube comprising the combination of an envelop comprising a metal section and an insulating section sealed to each other, a conductive member within said 60 envelop, joined to said metal section and extending spaced away from the envelop past the joint between said conductive and insulating sections, said tube being evacuated to a pressure so low that conduction 65 of electricity can occur by an electron discharge substantially independent of positive ionization, a cathode adapted to be operated at incandescence and a coöperating anode. 65

4. An electrical discharge device comprising the combination of an envelop consisting in part of metal and in part of insulating material, said envelop being exhausted to a pressure so low that conduction of electricity can occur therein by an electron discharge 70 operatively independent of positive ionization, a cathode operable at incandescence, an anode, and shielding means interposed between the cathode and the joint between the parts of said envelop for preventing the 75 accumulation of an electric charge on the insulating section adjacent said joint. 80

In witness whereof, I have hereunto set my hand this 12th day of June, 1916.

WILLIAM D. COOLIDGE.
